SEAR-CONTROL MEANS FOR FIREARMS

Harry L. Crockett, New Haven, Conn., assignor
to Olin Industries, Inc., New Haven, Conn., a
corporation of Delaware

Application September 2, 1948, Serial No. 47,361

10 Claims. (Cl. 42—18)

1

The present invention relates in general to firearms, and, more especially, to sear-control means by which the sear may be stopped normally after releasing the firing-means but which will permit additional displacement of the sear for the purpose of withdrawing the action from the chamber of the receiver.

An object of the invention is to provide a superior sear-control device for firearms which is inexpensive to manufacture and simple and reliable in operation.

A further object of the invention is to provide an improved sear-control device for bolt-action firearms wherein the device has the multiple functions of a sear-stop, a bolt-stop control-means, and means for latching a box-magazine in the frame of the firearm.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken side elevation of a bolt-action firearm embodying the improved sear-control device of this invention, the stock and associated parts of the firearm being omitted;

Fig. 2 is a broken side elevation in section of the firearm, similar to Fig. 1, and showing the action closed and the firing-pin held in cocked position by the sear, the improved sear-control device serving as a latch to hold the box-magazine in the frame of the firearm;

Fig. 3 is a broken side elevation in section, similar to Fig. 2, but showing the sear-stop deflected from its normal position by the sear which has been pulled downwardly out of the path of the bolt so as to permit withdrawal thereof from the receiver;

Fig. 4 is a perspective view of the sear-and-trigger unit;

Fig. 5 is a perspective view of the improved sear-control device of this invention; and

Fig. 6 is a perspective view of the box-magazine frame of the firearm.

The improved sear-control device of this invention is suitable for use in various firearm structures, but for the purposes of disclosure is shown used with the so-called "upturn-and-pullback" bolt-action firearm of the type disclosed more fully in the Crockett Patent No. 2,174,971 of October 3, 1939.

Referring especially to Figs. 1 and 2, the fire-

arm includes, in brief, a receiver 10 of tubular form, into the forward end of which the rear end of a barrel 11 is threaded or otherwise secured. The receiver 10 is also provided with an axial bolt-receiving passage 12, the forward upper portion of which is intersected by a transverse loading-and-ejection opening 13.

Mounted in the bolt-receiving passage 12 of the receiver 10 with capacity for reciprocation therein is a cylindrical bolt 14 provided with a longitudinally-axial firing-plunger guideway 15 which is intersected at its forward end by a relatively-small eccentric firing-point passage 16. Projecting through the passage 16 is the firing point 17 formed at the forward end of a firing-plunger 18, the latter being mounted in the guide-passage 15 in the bolt 14, with capacity for reciprocation therein relative to said bolt.

The rear portion of the breech-bolt 14 is reduced in diameter in the manner characteristic of firearms of this type, to provide a smooth cylindrical exterior surface upon which turns a bolt-operating sleeve 19 having a laterally-offset operating-handle 20 terminating in a ball-grip 21. The bolt-operating sleeve 19 is adapted to be held in place upon the reduced rear-end portion of the bolt 14 by means of a retaining sleeve 22 which is mounted upon the reduced rear-end portion of the bolt and secured in place thereon by a transverse retaining-pin 23.

The reduced rear-end portion of the bolt is provided with an axial aperture 24 constituting an extension of the aperture 15 of the bolt for accommodating a helical firing-spring 25 which bears at its forward end against the rear end of the firing-plunger 18 and at its rear end against an end-plug 26 secured in the rear end of the axial aperture 24 by the aforesaid transverse pin 23. The main portion of the firing-plunger 18 is substantially plate-like and is provided at its rear end with an upwardly-extending guide-rib 27 adapted to ride in a longitudinal groove formed in the upper wall of the reduced portion of the breech-bolt. The firing-plunger 18 is also formed at its rear end with a downwardly-extending guide-projection 28 which extends through a longitudinal slot in the bottom wall of the reduced portion of the breech-bolt, the guide-projection 28 having, in turn, a downwardly-extending lug 29 which is adapted to project into operative engagement with a cam-slot 30 formed in the bolt-operating sleeve 19.

Formed on the underside of the firing-plunger 18 is a forwardly-facing cocking-shoulder 31 which is adapted to be engaged by a rearwardly-

facing cocking-shoulder 32 formed upon the upwardly-projecting comb 33 of the sear-arm 34 of a sear-and-trigger unit, indicated generally by the numeral 35. Referring especially to Fig. 4, the sear-and-trigger unit 35 includes, in addition to the sear-arm 34, a trigger-arm 36 which depends from the rear end thereof substantially perpendicular thereto and terminates at its lower end in a curved trigger or finger-piece 37; and a safety-slide 38 mounted for limited longitudinal movement on the underside of the sear-arm 34. To this end, the rear end of the safety-slide is slotted longitudinally, as indicated at 39, to form two laterally-spaced guide-fingers 40—40, the inner edges of which are adapted to ride in suitable guide-grooves 41—41 formed at the intersection of the trigger-arm 36 with the sear-arm 34. The forward end of the safety-slide is held against the underside of the sear-arm 34 by the head 42 of a screw, the shank of which extends freely through a longitudinal slot 43 of the safety-slide and is secured in the underside of the sear-arm 34. A vertical slot 44 is formed in one of the guide-fingers 40 of the safety-slide and is adapted to receive the depending-finger 45 of a manually-operable safety-slide operating-arm 46, pivotally mounted on the pivot-pin 47 of the sear-and-trigger unit 35 hereinabove described. The forward end of the safety-slide 38 is provided with a down-turned lip 48 which, by manual movement of the operating-arm 46, is adapted to be moved into and from engagement with a shoulder of a box-magazine frame, as and for the purpose hereinafter described. The forward end of the sear-arm 34 is provided with a forwardly-extending nose 49, the underside 50 of which constitutes a substantially-horizontal bearing-surface adapted to rest upon the upper end of a sear-spring 51 which is adjustably mounted in a vertical aperture in the rear end of the aforementioned box-magazine frame and provides the force for yieldingly holding the rearwardly-facing cocking-shoulder 32 of the sear-comb 33 in engagement with the forwardly-facing cocking-shoulder 31 of the spring-loaded firing-plunger 18.

In this connection, it will be noted that the forward end of the sear-arm 34 and specifically the sear-comb 33 and sear-nose 49 are supported within a vertical slot 52 in the underside of the receiver for movement therein to engage the cocking-shoulder 32 of the sear-comb 33 with and to disengage it from the cocking-shoulder 31 of the firing-plunger.

The particular firearm shown herein is adapted to be provided with a box-type magazine, and to this end the underside of the receiver is provided with a second vertical slot 53 forwardly of the slot 52 and intersecting the bolt-passage 12 of the receiver. Mounted on the underside of the receiver and opposite its slot 53, is a box-magazine frame, indicated generally at 54 in Fig. 6, for releasably supporting a box-magazine 55. The latter is of conventional construction embodying substantially-flat side-plates 56—56, and arcuate front and rear end walls 57 and 58 respectively joined to the side-plates, the front and rear walls being set inwardly slightly of the front and rear edges 59 and 60 respectively of the side-plates 56—56, so as to form channels 61 and 62. A pair of substantially-rectangular notches 63 are formed in the oppositely-disposed edges 60 of the channel 62 for accommodating lugs of the box-magazine latching-means hereinafter described.

Referring in particular to Fig. 6, the box-magazine frame 54 comprises a substantially-

rectangular block divided into front-end and rear-end portions 64 and 65 respectively by a box-magazine receiving-aperture 66 formed vertically in the right-hand side of the frame, the forward and rearward walls 67 and 68 respectively of the aperture 66 sloping downwardly and forwardly to conform to the curvature of the front and rear end walls 57 and 58 respectively of the box-magazine 55, the curved walls of the aperture 66 being formed with longitudinal ribs 69 and 70 respectively, for engaging in the respective channels 61 and 62 of the box-magazine. The front end 64 of the frame 54 is notched on its underside, as is shown especially well in Figs. 1 and 2, and is provided with a vertical aperture 71 for accommodating an assembly-screw 72 adapted to secure the front end 64 of the frame to the underside of the receiver, with the vertical aperture 66 of the frame in alignment vertically with the slot 53 in the bottom of the receiver for accommodating the upper end of the box-magazine. The rear-end portion 65 of the frame 54 is also provided with a vertical aperture 73 to receive an assembly-screw 74 by which the rear-end portion of the frame is secured to the underside of the receiver immediately rearwardly of its vertical aperture 53. In this connection, it will be noted that the upper surface of the frame 54 is formed with a slightly-concave cylindrical surface of revolution, the curvature of which corresponds to the curvature of the underside of the receiver, so that the frame may make a snug fit therewith when assembled thereon by the screws 72 and 74.

A longitudinal clearance-recess 75 is provided in the upper surface of the frame, the clearance-recess being substantially U-shaped in cross section at its intersection with the rear end of the frame, and the bottom of the recess sloping upwardly and forwardly from its intersection with the rear end of the frame, to intersect the upper concave surface thereof. Formed in the upwardly-sloping bottom of the clearance-recess 75 is a substantially-vertical internally-threaded aperture 76 which is adapted to accommodate an adjusting-screw 77 which, in turn, supports the aforementioned sear-spring 51 in the aperture 76 with its upper end in engagement with the underside 50 of the sear-nose 49. In this connection, it will be noted that the clearance-recess 75 of the frame is immediately opposite the vertical slot 52 in the underside of the receiver which accommodates the sear-nose 49 of the sear-and-trigger unit 35.

Cooperatively associated with the box-magazine and the sear-and-trigger unit of the firearm is the sear-control means of this invention, which serves both as a sear-stop and as a latch for releasably securing the box-magazine in the frame of the firearm. The sear-control means is indicated generally at 78, and, as shown in detail in Fig. 5, is a substantially Z-shaped member formed of flat sheet-metal stock and comprising a substantially-rectangular leaf-portion 79 which constitutes, in effect, a relatively-stiff leaf-spring adapted to be assembled securely on the underside of the frame 54 by means of the aforesaid assembly-screw 74, the latter extending up into the rear end of the frame through a vertical aperture 80 formed at the forward end of the leaf-spring portion 79 of the sear-control device.

In order to prevent pivotal movement of the latter with respect to the frame, the forward end of the leaf-spring 79 is formed with upstanding transversely-spaced parallel ears 81—81 adapted

to extend upwardly along opposite sides respectively of the frame 54. Formed integrally at the forward end of the leaf-spring 79 of the sear-control device and bent downwardly and forwardly therefrom, is a resilient reach 82, the lowermost end of which is curved backwardly and upwardly upon itself to provide a finger-engaging portion 83 for flexing the resilient reach 82. Extending transversely from opposite edges respectively of the resilient reach 82, intermediate its upper and lower ends, is a pair of latching-lugs 84, each of which is adapted to lockingly engage in one of the notches 63 formed in the corresponding vertical flanges 60 of the rear channel 62 of the box-magazine, the latching-lugs 84 serving to releasably secure the box-magazine in the aperture 66 of the frame 54 with the upper end of the box-magazine extending into the bolt-passage 12 of the receiver, for feeding cartridges into cartridge-chambering position.

The rear end of the leaf-spring 79 is formed with an integral upstanding reach 85, the upper edge 86 of which constitutes an abutment hereinafter referred to as a "sear-stop." The latter is adapted to be located beneath the underside of the sear-arm 34 and, more particularly, the underside of the safety-slide 38 intermediate its screw 42 and its lip 48, and to be spaced vertically from the underside of the safety-slide normally a distance such as to permit unrestrained movement of the sear-and-trigger unit when releasing the cocked firing-plunger.

As noted above, if after the firearm is cocked, it should be desired to lock the sear-and-trigger unit 35 against operation by its finger-piece 37, the manually-operated safety-arm 46 is pivoted rearwardly or to its "on" position, thereby moving the safety-slide 38 forwardly on the underside of the sear-arm 34 so as to engage the lip 48 of the slide with a fixed part of the frame and more particularly with the shoulder 87 at the rear edge of the clearance-recess 75 thereof. Under these conditions, the sear-and-trigger unit 35 is positively held from pivotal movement clockwise, thereby preventing release of the cocked firing-plunger 18. When the safety-arm 46 is swung forwardly to its "off" position, the safety-slide 38 will be retracted, thereby withdrawing its lip 48 from engagement with the shoulder 87 of the frame 54. Under these conditions, the sear-and-trigger unit is free to be rocked clockwise by pulling rearwardly on the finger-piece 37 against the compression force of the sear-spring 51 to release the cocked firing-plunger 18 and thus effect firing of the arm.

In rocking the sear-and-trigger unit clockwise to release the sear, the sear-arm 34 will swing downwardly until the underside of the sear-arm, and more particularly the safety-slide mounted thereon, is brought into engagement with the upper edge or abutment 86 of the upstanding reach of the relatively-stiff leaf-spring 79. Due to the inherent stiffness of this resilient element of the sear-control means, a substantially-normal pull on the finger-piece 37 of the sear-and-trigger unit will be insufficient to cause the sear-arm to displace the sear-abutment 86, whereby the latter serves effectively as a positive stop to limit further displacement of the sear-arm. On releasing the finger-piece of the sear-and-trigger unit, the compressed sear-spring 51 will elevate the forward end of the sear-arm into the vertical slot 52 of the receiver for re-engagement of the cocking-shoulder 32 of the sear-comb 33 with the cocking-shoulder 31 of the firing-plunger 18.

In order that the action or bolt 14 may not inadvertently slide out of the receiver when unlocked therefrom, the sear-comb 33 is provided at its forward upper edge with a shoulder or bolt-stop 88 adapted normally to project up into a clearance-aperture 89 formed in the breech-bolt intermediate its reduced rear-end portion and its head-portion 90, the bolt-stop 88 being adapted to project up into the path of the rearwardly-facing shoulder 91 of the latter, both when the sear is in locking engagement with the firing-plunger and when the sear-arm has been pulled down into engagement with the sear-stop abutment 86 to fire the arm, as hereinabove described.

Assuming the sear to be in its latter position, then if the breechblock is unlocked and pulled rearwardly, the rearwardly-facing shoulder 91 of the head portion 90 of the bolt will bring up against the bolt-stop 88 of the sear-comb 33, which prevents inadvertent removal of the breech-bolt from the receiver. However, should it be desired to remove the bolt from the receiver intentionally as, for example, when disassembling the elements of the firearm, the shooter may lower the bolt-stop 88 of the sear-comb out of the path of the rearwardly-facing shoulder 91 of the breech-bolt by exerting more than the normal rearward pull on the finger-piece 37 of the sear-and-trigger unit, thereby pulling the sear-arm 34 downwardly against the sear-stop abutment 86 with sufficient force to overcome the resistance of the relatively-stiff leaf-spring 79 to deflect the latter downwardly, as indicated in Fig. 3, whereupon the bolt-stop 88 of the sear-comb will lie below the rearwardly-facing shoulder 91 of the bolt-head to permit withdrawal of the bolt from the receiver.

From the foregoing it will be seen that by the construction and arrangement of the elements of the sear-control means 78, a relatively-simple, inexpensive, unitary device is provided, incorporating the functions of a sear-stop and box-magazine latching-member, both of which are of durable construction and adapted to be mounted in operative relationship with other elements of the firearm by a single fastening-means. Further, that when assembled to the underside of the box-magazine frame, the leaf-spring portion 79 of the sear-stop means extends over the kerfed end of the adjusting-screw 77 of the sear-spring 51 so as to hide the screw and prevent maladjustment of the sear-spring by those inexperienced with firearms; and that by forming the sear-stop as an inherent part of a resilient leaf-spring, the sear-stop abutment is operable also as a bolt-stop control-means for permitting the intentional removal only of the bolt from the receiver.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine engageable in said frame; and sear-control means comprising a resilient member having a sear-abutment and

a latch-means, said resilient member being arranged normally to support said sear-abutment in the path of said sear to stop the displacement of said sear after disengagement thereof from said cocked spring-pressed firing-member, and to hold said latch-means in engagement with said box-magazine thereby to releasably secure the latter in said frame.

2. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine engageable in said frame; sear-control means comprising a resilient member having a sear-abutment and a latch-means, said resilient member being arranged normally to support said sear-abutment in the path of said sear to stop the displacement of said sear after disengagement thereof from said cocked spring-pressed firing-member, and to hold said latch-means in engagement with said box-magazine thereby to releasably secure the latter in said frame; and fastening-means arranged to secure said sear-control means to said frame.

3. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine engageable in said frame; and sear-control means comprising a unitary leaf-spring member having a sear-abutment at one extremity thereof and a latch-means at the opposite extremity thereof, said leaf-spring member being arranged normally to support said sear-abutment in the path of said sear to stop the displacement of said sear after disengagement thereof from said cocked spring-pressed firing-member, and to hold said latch-means in engagement with said box-magazine thereby to releasably secure the latter in said frame.

4. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine engageable in said frame; sear-control means comprising a unitary leaf-spring member having a sear-abutment at one extremity thereof, and a latch-means at the opposite extremity thereof, said leaf-spring member being arranged normally to support said sear-abutment in the path of said sear to stop the displacement of said sear after disengagement thereof from said cocked spring-pressed firing-member, and to hold said latch-means in engagement with said box-magazine thereby to releasably secure the latter in said frame; and single fastening-means engageable with said frame and said unitary leaf-spring member to secure the latter to said frame.

5. In a firearm, including in combination: a movable bolt; a frame; a spring-pressed firing-member; a sear-and-trigger unit arranged to releasably hold said spring-pressed firing-member in its cocked position and comprising a sear-arm having a sear and a bolt-stop at one extremity thereof and a finger-piece at the opposite extremity thereof for operating said sear and said bolt-stop; a box-magazine engageable in said frame; and sear-control means comprising a resilient member having an abutment and a latch-means, said resilient member being arranged normally to support said abutment opposite said sear-arm to stop the displacement of said sear-arm after disengagement thereof from said cocked spring-pressed firing-member.

5 engagement of said sear from said cocked spring-pressed firing-member thereby to retain said bolt-stop in the path of movement of said bolt and prevent inadvertent removal thereof from said firearm, said resilient member being arranged to be flexed by said sear-arm by exertion of an abnormal force on the finger-piece of said sear-and-trigger unit thereby to displace said bolt-stop from the path of movement of said bolt to permit intentional removal thereof from said firearm, said resilient member being arranged also to hold said latch-means in engagement with said box-magazine so as to releasably secure the latter in said frame.

10 6. In a firearm, including in combination: a movable bolt; a frame; a spring-pressed firing-member; a sear-and-trigger unit arranged to releasably hold said spring-pressed firing-member in its cocked position and comprising a sear-arm having a sear and a bolt-stop at one extremity thereof and a finger-piece at the opposite extremity thereof for operating said sear and said bolt-stop; a box-magazine engageable in said frame; and sear-control means comprising a unitary leaf-spring member having an abutment at one extremity thereof and a latch-means at the opposite extremity thereof, said leaf-spring member being arranged normally to support said abutment opposite said sear-arm to stop the displacement of said sear-arm after disengagement of said sear from said cocked spring-pressed firing-member thereby to retain said bolt-stop in the path of movement of said bolt and prevent inadvertent removal thereof from said firearm, said leaf-spring member being arranged to be flexed by said sear-arm by exertion of an abnormal force on the finger-piece of said sear-and-trigger unit thereby to displace said bolt-stop from the path of movement of said bolt to permit intentional removal thereof from said firearm, said leaf-spring being arranged also to hold said latch-means in engagement with said box-magazine so as to releasably secure the latter in said frame.

15 7. In a firearm, including in combination: a movable bolt; a frame; a spring-pressed firing-member; a sear-and-trigger unit arranged to releasably hold said spring-pressed firing-member in its cocked position and comprising a sear-arm having a sear and a bolt-stop at one extremity thereof and a finger-piece at the opposite extremity thereof for operating said sear and said bolt-stop; a box-magazine engageable in said frame; sear-control means comprising a unitary leaf-spring member having an abutment at one extremity thereof and a latch-means at the opposite extremity thereof, said leaf-spring member being arranged normally to support said abutment opposite said sear-arm to stop the displacement of said sear-arm after disengagement of said sear from said cocked spring-pressed firing-member thereby to retain said bolt-stop in the path of movement of said bolt and prevent inadvertent removal thereof from said firearm, said leaf-spring member being arranged to be flexed by said sear-arm by exertion of an abnormal force on the finger-piece of said sear-and-trigger unit thereby to displace said bolt-stop from the path of movement of said bolt to permit intentional removal thereof from said firearm, said leaf-spring being arranged also to hold said latch-means in engagement with said box-magazine so as to releasably secure the latter in said frame; and single fastening-means engageable with said frame and said unitary leaf-spring member to stop the displacement of said sear-arm after disengagement thereof from said cocked spring-pressed firing-member.

8. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine having a notch therein and engageable in said frame; and sear-control means comprising a unitary leaf-spring having a first resilient reach provided with a sear-abutment and a second resilient reach opposite said first resilient reach and provided with a latching-lug, said first resilient reach being arranged normally to support said sear-abutment in the path of said sear to stop the displacement of said sear after disengagement thereof from said cocked spring-pressed firing member, said second resilient reach being arranged to releasably hold said latch-lug in the notch of said box-magazine to secure said magazine in said frame.

9. In a firearm, including in combination: a frame; a spring-pressed firing-member; a sear-and-trigger unit arranged to releasably hold said spring-pressed firing-member in its cocked position and comprising a sear, and a finger-piece for operating said sear; a box-magazine having notches therein and engageable in said frame; sear-control means comprising a unitary leaf-spring having a first resilient reach provided with a sear-abutment and a second resilient reach opposite said first resilient reach and provided with latching-lugs, said first resilient reach being arranged normally to support said sear-abutment in the path of said sear to stop the displacement of said sear after disengagement thereof from said cocked spring-pressed firing-member, said second resilient reach being arranged to releasably hold said latching-lugs in the notches of said box-magazine to secure said magazine in said frame; and fastening-means engageable with said frame and said unitary leaf-spring member intermediate said sear-abutment and said latch-

10
ing-lugs to secure said unitary leaf-spring member to said frame.

10. In a firearm, including in combination: a receiver; a bolt movable in said receiver; a frame secured to said receiver; a spring-pressed firing-member; a sear-and-trigger unit arranged to releasably hold said spring-pressed firing-member in its cocked position and comprising a sear-arm having a sear and a bolt-stop at one extremity thereof and a finger-piece at the opposite extremity thereof for operating said sear and said bolt-stop; a box-magazine having notches therein and engageable in said frame; sear-control means comprising a unitary leaf-spring having a first resilient reach provided with an abutment and a second resilient reach in axial alignment with said first resilient reach and provided with latching-lugs, said first resilient reach being arranged normally to support said abutment below said sear-arm to stop the displacement of said sear-arm after disengagement of said sear from said cocked spring-pressed firing-member thereby to retain said bolt-stop in the path of movement of said bolt and prevent inadvertent removal thereof from said receiver, said first resilient reach being arranged to be flexed by said sear-arm by exertion of an abnormal force on the finger-piece of said sear-and-trigger unit thereby to displace said bolt-stop from the path of movement of said bolt to permit intentional removal thereof from said receiver, said second resilient reach being arranged to releasably hold said latching-lugs in the notches of said box-magazine to secure said magazine in said frame; and a single fastening-means engageable with said frame and said unitary leaf-spring intermediate said abutment and said latching-means to secure the unitary leaf-spring to said frame.

HARRY L. CROCKETT.
